(57) **CLAIM**

I claim the ornamental design for a clamp rod, as shown and described.

DESCRIPTION

FIG. 1 shows a straight end view of the invention;
FIG. 2 shows a low perspective view thereof;
FIG. 3 shows a side perspective thereof; and,
FIG. 4 shows a high perspective view thereof.

The broken lines present in the drawings are used to show a boundary and make up no part of the claimed invention. The oblique lines on the face of the rod are used to show the sheer face of the rod and make up no part of the claim invention.
